UNITED STATES PATENT OFFICE.

EDWIN L. GODING, OF SPRINGVALE, MAINE, ASSIGNOR TO O. A. MILLER TREEING MACHINE COMPANY, OF PORTLAND, MAINE, A CORPORATION OF MAINE.

LAST.

1,048,525.

Specification of Letters Patent. Patented Dec. 31, 1912.

Application filed August 23, 1902. Serial No. 120,736.

To all whom it may concern:

Be it known that I, EDWIN L. GODING, a citizen of the United States, residing at Springvale, in the county of York and State of Maine, have invented an Improvement in Lasts, of which the following description, in connection with the accompanying drawings, is a specification, like letters on the drawings representing like parts.

10 My invention aims to provide a novel and improved last; one which shall combine the advantageous features both of the "hinged last" so called, and the older form of block last, without the disadvantageous features 15 of either.

The nature of my invention will best be understood from a description of a last illustrating one embodiment thereof, it being understood, however, that my invention 20 is not restricted to the particular embodiment disclosed.

In the accompanying drawing,—Figure 1, in side elevation, shows a last illustrating my invention, the instep and heel portions 25 shown by dotted lines in their abnormal positions preparatory to insertion or removal of the last, and, Fig. 2, a top view thereof.

The last shown in the drawing comprises the fore part, *a*, heel part *b*, and instep part 30 *c*, usually called the "instep block." The fore and heel parts are adapted to swing one relative to the other to shorten the last. As herein shown, the heel part is provided with one or more forwardly extending plates 35 or hinge pieces, *d*, pivoted at *d'*, to the fore part. This pivot may be located at any desired point or level, but I prefer to locate it quite close to the bottom of the last and below the point at which the last would 40 sustain itself against collapse, thus to obtain the maximum shortening of the last for a given relative swinging movement of the fore and heel parts.

The instep block, *c*, as here shown, laps 45 both the fore part and heel part, and when in position, held by the upper lasted or laced above it, effectually guards against accidental collapse of the last. The instep block, *c*, may be secured in position against 50 sliding movement in either direction by any of the well known means. I prefer, however, to give to the secant line along which the said instep block is divided from the remaining body of the last, such a sweep or

direction as shall present, at some point in 55 its length, a slide resisting surface. In the last shown, this secant line is indicated at 1, said line being given a sweep at 2, to provide opposite locking or slide resisting surfaces which coöperate respectively with the locking surface 3, on the fore part, and 4 on the heel part to hold the said block firmly in position.

By forming the locking or slide resisting surfaces on the instep block, with sweeps or 65 curves where they blend with the secant line, of which they really form a part, I am enabled to divide the instep block from the remaining body portion of the last by a saw traveling throughout in one direction so that 70 the formation of such locking or slide resisting surfaces adds practically nothing to the cost of dividing the last at this point. A locking or slide resisting surface at 2—3, 75 obviates the necessity for the usual pin at the toe end of the instep block and the surface 2—4, likewise obviates the necessity for a spring locking or other pin or device at the top end of the said block.

By sliding the instep block upward, with 80 or without turning it into its dotted position, Fig. 1, the waist measurement of the last may be reduced, as with the ordinary block last, which is desirable for the most ready withdrawal of the last from or its 85 insertion in a shoe. And the subsequent insertion of the block fills out the shoe across the instep in a manner peculiar to lasts of the removable block type and not always attainable in the ordinary hinge last having 90 a solid fore part.

It will be noted that the instep block *c* is so proportioned and the surfaces 1 and 4 are so shaped that during the first part of the backward movement of the block the 95 depth of the last from the shank to the instep engaging surface will be increased. The last shown is so designed that this increase at the upper part of the instep will continue until the corner at the right of the, 100 surface 2, Fig. 1, passes above the upper face of the heel part. Beyond this point a rapid decrease in the depth of the last through the instep will take place. This construction insures the retention of the instep block in operative position without the 105 employment of the usual locking devices.

Having removed the instep block, the heel

part may be turned upward, as in dotted lines, Fig. 1, to shorten the last, as in the ordinary hinge last, and facilitate insertion and withdrawal. The instep block, for convenience, may be connected by a cord, *e*, with the heel part, to retain the separated parts together, when not in use. The line of division *s*, between the fore and heel parts is so located or directed, relative to the pivot *d'*, that the upward turning movement of the heel part is limited to substantially the extent indicated in dotted lines, by contact of the front face of the heel part with the rear face of the fore part, near the top of the latter. This is useful in turn shoe work, as it enables the laster to strike the last at its heel, upon the bench, and drive the fore part into position, as with the use of the ordinary block last. Obviously this could not be done with the ordinary hinge last, which would at once collapse if any attempt were made to drive it endwise into place, unless some special locking device were used, which is unnecessary with my last.

My invention is not restricted to the particular embodiment thereof herein shown and described, but may be varied without departing from the spirit and scope of said invention.

Claims:

1. A last comprising complementary-shaped fore part, heel part and instep part, the contacting surfaces of said parts being formed to resist collapse of the last.
2. A multipart last comprising relatively movable fore and heel portions and a slideable instep block having a slide resisting surface coöperating with the top and rear of said fore portion.
3. A last comprising complementary-shaped instep part and fore part, said instep part tapering to a thin edge at its forward end and a heel part movably connected to said fore part and in the operative position of the parts held from upward movement by said instep part, the contacting surfaces of said instep part and fore part being formed to resist downward movement of the instep part upon the fore part.
4. A multipart last comprising a fore part, a heel part, and an instep block presenting

near the rear end of its secant face slide and heel part resisting surfaces.

5. A last comprising a fore part, a heel part hinged to said fore part near the sole of the last, said last being recessed at the upper region of juncture of said fore part and heel part, and an instep block for completing the instep portion of the last arranged to have engagement in its operative position with the heel part and having a projection to enter said recess, the contacting surfaces of the parts being formed to resist relative movement of said parts.

6. A last comprising a fore part, a heel part movably connected to the fore part, and a removable block for completing the instep portion of the last having engagement in its operative position with the fore part and the upper portion of the heel part, said fore part and block having, upon their contacting surfaces intermediate the ends of the block, interlocking portions extending from one side to the other of the last and formed to resist forward movement of the block.

7. A multipart last comprising fore and heel parts and an instep block provided with oppositely acting locking surfaces engaging the adjacent faces of the fore and heel parts respectively.

8. A multipart last comprising a fore part and a heel part hinged together, and an instep block the secant face of which presents, at points adjacent the junction of the fore and heel parts, oppositely disposed locking surfaces.

9. A multipart last comprising a relatively movable forepart and heel part, and an instep block, the secant surface of said block presenting curved faces at or near its rear end formed to resist forward movement of the block, said block and surface being formed to present dimensions from the shank to the instep engaging surface that are increased when the block is moved backwardly from its normal position.

In testimony whereof, I have signed my name to this specification, in the presence of two subscribing witnesses.

EDWIN L. GODING.
